APPARATUS FOR NOTCHING OR SLOTTING
PERFORATED CARDSHunter E. Hooe, Athens, Ohio, assignor to The
McBee Company, Athens, Ohio, a corporation

Application September 8, 1947, Serial No. 772,725

6 Claims. (Cl. 164—111)

1

The present invention relates to apparatus for selectively and simultaneously notching or slotting cards or the like having marginally arranged perforations. Such cards are of the general type known as "Keysort" cards.

An object of the present invention is to provide a gang punch of simple construction, relatively few parts and ease of operation for simultaneously notching or slotting a card from one of its edges to selected perforations arranged inwardly of such edge.

Another object of the invention is to provide a gang punch embodying punch or cutter operating elements which are individually selectable to be placed in operative positions or to be held in inoperative positions.

A further object of the invention is to provide a gang punch embodying punch or cutter operating elements which are individually movable and located selectively in operative or inoperative positions, the elements being held positively in one position or the other by a common instrumentality.

One form which the invention may assume is exemplified in the following description and illustrated by way of example in the accompanying drawings, in which:

Fig. 1 is a perspective view of an embodiment of the invention, parts being broken away to disclose interior mechanisms.

Fig. 2 is a transverse vertical section through the apparatus disclosed in Fig. 1.

Fig. 3 is a partial plan view of a portion of a marginally punched perforated card, which has been notched or slotted in the foregoing apparatus.

As disclosed in the drawings, the apparatus is essentially a gang punch for notching the marginal portions of cards 16 from an outer edge 11 inwardly to selected perforations 12 arranged parallel to such edge to form a pattern of notches or slots 13 pertaining to a single classification. The machine is designed for simultaneously notching the cards in each group of classifications to indicate certain indicia representing the different classifications.

The apparatus for notching the cards 10 in the manner indicated includes a generally horizontal base 14, having a longitudinal opening 15 across which a plate or platen 16 extends, being secured to the base in any suitable manner, as by use of screws 17 or the like. The platen or die plate 16 is provided with a plurality of die recesses or cavities 18 parallel to each other and opening into the elongated hole 15 in the base, into and

2

through which the card punched material may fall. The center-to-center distance between adjacent die cavities 18 is the same as the center-to-center distance between the perforations 12 on the cards to be notched, there being suitable guide means provided in the apparatus for insuring ready placement of the cards with the perforations 12 in registry with the die cavities 18 and with the row of perforations disposed inwardly over the cavities to a suitable extent to insure notching from the edge 11 of the card into the perforations 12.

The die cavities 18 are formed by cutting or shearing spring-like cutters, punches or shearing blades 19 from the plate 16, with the rearward portions 19a of the cutters, punches or shearing blades remaining integral with the plate. It is apparent from the drawings that the cutters 19 are forced upwardly from the plane of the plate 16 a sufficient distance to permit entry thereunder of the marginal portion of a card 10. The material from which the platen is made possesses spring-like characteristics, so that the punching of the cutters 19 from the platen and their deformation to an upper position results in cutters retaining their spring-like properties, the cutters 19, however, normally tending to remain in and reassume their elevated position above the main portion of the platen 16.

Each cutter or shearing blade 19 is actuatable downwardly into its aligned die recess or cavity 18 by an individual operating lever 20, having a depending forward nose 21 adapted to rest upon the upper surface of the cutter 19 and a body portion 22 extending parallel to and above the cutter, such portion being provided with an elongated slot 23 receiving a pin 24 common to all of the levers and extending along the entire length of the machine and supported at its ends within the vertical side members or arms 25 extending upwardly from the base 14 of the apparatus. The operating levers 20 are adapted to move in vertical planes to shift the punches 19 downwardly into the die cavities 18, being guided in such movement by forward and rearward ribs, fins or fingers 26 depending across the side faces of each operating lever 20 from a common supporting member 27 extending over all of the operating levers and suitably secured to the vertical arms 25 of the apparatus. It is apparent that the operating levers move within individual guide grooves defined by the depending ribs or fins 26.

To the rear of the supporting member 27, each operating lever 20 is provided with an upwardly extending lug 28. This lug can be held in its

forward position, to hold the nose 21 in a corresponding forward position in operative relation with respect to the associated spring-like cutter 19, by a detent bar or a retaining plate 29 extending across the machine and adapted to be located immediately behind one or more of the upright lugs 28 or immediately ahead of one or more of such lugs, for the purpose of either holding selected operating levers 20 forwardly in operative position or rearwardly in inoperative position.

The retaining plate 29 is secured to an L-shaped cover member 30, whose top portion 31 is adapted to extend over the guide member 27 and the major portion of the operating levers 20, forming a protective cover therefor, and whose back portion 32 is mounted upon hinge pins 33 secured to the arms 25 of the machine. When the L-shaped cover plate 30 is disposed over the guide member 27 and operating levers 20, as disclosed in Fig. 1 and in full lines in Fig. 2, the retaining plate 29 is disposed along either the forward or rearward ends of the operating lever lugs 28. When the cover plate 30 is moved upwardly about its pivot pins 33, the retaining plate 29 is removed from its position adjacent the lugs, as indicated in dotted lines in Fig. 2.

The slot 23 in each operating lever 20 is so disposed with respect to the fulcrum pin 24 about which the lever is swingable as to enable each operating lever to be shifted to a forward position, in which it is operative to actuate an associated punch or cutter blade 19, or it may be moved rearwardly on the fulcrum pin 24, in which position it is inoperative and cannot effect downward movement of a punch or cutter blade 19 into a mating die recess or cavity 18. The operating levers 20 which are disposed rearwardly, as indicated in dotted lines on Fig. 2, can effect no movement of their associated punches or cutters, while those disposed forwardly are capable of producing operation of their associated cutters or punches.

The latter are actuated by an eccentric device, consisting of a crank mechanism whose coaxial shaft portions 34 are rotatably mounted in suitable bearings provided in the forward portions of the vertical arms 25. The eccentric mechanism also includes an extended eccentric pin 35 disposed forwardly of the coaxial shafts 34 and adapted to engage all operating levers 20 which have been shifted to forward cutter actuating positions. One of the coaxial shafts 34, as the one at the right of the apparatus, extends through its vertical arm 25 to the exterior thereof, where a suitable lever 36 is affixed to it, having a bar 37 adapted to be depressed by the finger or hand of an operator to rock the shafts 34 in such direction as to move the eccentric pin 35 downwardly, correspondingly shifting the forward operating levers 20 downwardly, and moving the corresponding spring-like cutters 19 downwardly into the die cavities 18, to notch the card 10 from its edge 11 to the perforations 12 in alignment with the forwardly extending operating levers 20. Release of the pressure or force on the common operating lever 36 causes its return and return of all parts to their initial positions, because of the leaf spring force of the cutters 19, which inherently tend to return to their upper initial positions.

By swinging the cover plate 30 to the rear of the apparatus about its hinge pins 33, the retainer bar 29 is removed from its position adjacent the operating lever lugs 28, which then permits cer-

tain operating levers to be moved forwardly which are to effect slotting or notching of the card, and the remaining operating levers to be moved to or allowed to remain in their rearward positions, so as not to be operated upon by the eccentric pin 35 when it moves downwardly under the influence of the operating lever 36. Thereafter, the cover plate 30 is moved forwardly to its original position, which locates the retaining plate 29 immediately to the rear of the forwardly positioned operating lever lugs 28 and immediately ahead of the rearwardly disposed operating lever lugs. Accordingly, the forward operating levers 20 are prevented from moving rearwardly, in view of the engagement of their lugs 28 with the retaining plate 29, and the other operating levers are held in their inoperative positions, since their forward movement is prevented by engagement of the forward portions of their lugs 28 with the rear face of the retaining plate 29. It is, of course, apparent that the forward movement of the operating levers which have been selected for notching or slotting the card is limited by engagement of the ends of their slots 23 with the pin 24. It is also apparent that there is sufficient clearance between the lugs 28 and other parts of the forward operating levers and the guide member 26, 27 and retaining plate 29 to permit pivotal movement of the operating levers 20 on the pin 24.

Following forward movement of the operating levers 20 which are to effect slotting and notching of the card, and movement of the cover plate 30 to its initial locking or retaining position, the card 10 may be placed on the platen 16 and the lever operator 36 depressed, which will effect notching or slotting of the card in the manner described above. Thereafter, other cards may be notched or slotted in the same manner, or the operating lever 20 arrangement may be altered to effect a different notching pattern on one or more of such cards.

It is, accordingly, apparent that apparatus for notching or slotting perforated cards has been provided which is capable of simultaneously notching or slotting the cards to selected perforations by manipulation of a single lever or corresponding element. The operating mechanism of the apparatus may be variously selected to provide the notching of any indicia on the cards, depending upon the classification thereon desired. Such mechanism possesses few parts, is comparatively simple in construction, in its manner of selection to placing the levers in operating or non-operating positions, and in the mode in which simultaneous punching is effected.

While I have disclosed the preferred embodiment of my invention, it is to be understood that various changes may be made therein by those skilled in the art without departing from the spirit of the invention as defined in the appended claims.

Having thus described my invention, what I claim and desire to secure by Letters Patent is:

1. An apparatus for punching cards, including a member having parallel die cavities therein, spring-like punches integral with said member and in alignment with said cavities, individual punch operators engageable with said punches and movable in one direction therealong to operative positions and in the opposite direction therealong to inoperative positions, and common means for holding said punch operators in such forward and rearward positions.

2. An apparatus for punching cards, including

a member having parallel die cavities therein, spring-like punches integral with said member and in alignment with said cavities, individual operating levers engageable with said punches, means mounting said operating levers for swinging movement about a common axis and for selective movement in one direction along said punches to operative positions or in the opposite direction along said punches to inoperative positions, common means for holding said operating levers in such forward and rearward positions, and eccentric means for moving said forwardly positioned operating levers to shift their associated punches toward said die cavities.

3. An apparatus for punching cards, including a member having parallel die cavities therein, spring-like punches integral with said member and in alignment with said cavities, operating levers engageable with said punches, said operating levers having slots therein, a pivot pin extending through said slots to permit selective movement of said levers along said punches in one direction to operative positions or along said punches in the opposite direction to inoperative positions, means for holding said operative levers in such forward and rearward positions, and eccentric means engageable with said forwardly positioned operating levers to shift their associated punches toward said die cavities.

4. An apparatus for punching cards, including a member having parallel die cavities therein, spring-like punches integral with said member and in alignment with said cavities, individual operating levers engageable with said punches and having slots, a pivot pin extending through said slots to enable selective movement of said operating levers along said punches in one direction to operative positions or along said punches in the opposite direction to inoperative positions, lugs extending from said levers, common holding means adapted to be disposed adjacent the rear of the lugs on said forwardly extending levers and adjacent the front of the lugs of said rearwardly positioned levers to hold said levers in their respective selected positions, and means for moving said forwardly positioned operating levers to shift their associated punches toward their associated die cavities.

5. An apparatus for punching cards, including a flat horizontally disposed plate having a plurality of parallel portions therealong struck out

5 to provide parallel die cavities and overlying punch elements integrally joined at one set of ends with the flat plate, means for selectively driving the punch elements toward the die cavities, said means including elongated horizontally disposed individual punch operators resting at one set of ends on and supported by the free ends of the punch elements and being movable along the punch elements to and from active positions, 10 a lost-motion pivotal connection for each punch operator for allowed movement of the operators to and from their active positions and toward the die cavities, and means for actuating the actively disposed punch operators to drive the associated punch elements toward the die cavities.

15 6. An apparatus for punching cards, including a flat horizontally disposed plate having a plurality of parallel portions therealong struck out to provide parallel die cavities and overlying 20 punch elements integrally joined at one set of ends with the flat plate, means for selectively driving the punch elements toward the die cavities, said means including elongated horizontally disposed individual punch operators resting at 25 one set of ends on and supported by the free ends of the punch elements and being movable along the punch elements to and from active positions, a single pivot rod extending through horizontally elongated slots formed in the punch operators 30 to permit movement of the punch operators to and from their active positions and toward the die cavities, and an eccentric bar rotatable for moving the actively disposed punch operators toward the die cavities to drive the associated 35 punch elements toward the die cavities.
